UNITED STATES PATENT OFFICE.

JOHN J. CAMPBELL AND HIRAM C. JOHNSON, OF BUTLER, PENNSYLVANIA,
ASSIGNORS TO T. W. PHILLIPS MANUFACTURING COMPANY, OF BUT-
LER, PENNSYLVANIA, A CORPORATION OF PENNSYLVANIA.

CLUTCH.

No. 823,260.

Specification of Letters Patent.

Patented June 12, 1906.

Application filed December 28, 1905. Serial No. 293,634.

To all whom it may concern:

Be it known that we, JOHN J. CAMPBELL and HIRAM C. JOHNSON, citizens of the United States of America, residing at Butler, in the county of Butler and State of Pennsylvania, have invented certain new and useful Improvements in Clutches, of which the following is a specification, reference being had therein to the accompanying drawings.

This invention relates to certain new and useful improvements in clutches; and the primary object of the invention is to provide a clutch for pulley-wheels which will be positive in its action, simple and inexpensive, and free from all danger of being rendered inoperative by constant use.

Our invention aims to provide positive and reliable means for temporarily fixing a pulley-wheel upon a shaft and easily and quickly releasing the same at any desired time. In this connection our improved clutch is adapted to be manually operated to grip a pulley-wheel, and in releasing a pulley-wheel the clutch is automatically actuated by gripping a portion of the same. To this end we employ a conventional form of pulley-wheel, shaft, and gripping-shoes to engage a pulley-wheel, and in connection with these elements we have devised novel mechanism for easily and quickly actuating the shoes to grip a pulley, said mechanism being automatically actuated to release said shoes when a portion of the same is held stationary.

With the above and other objects in view the invention consists in the novel construction, combination, and arrangement of parts to be hereinafter more fully described and then specifically pointed out in the claims, and, referring to the drawings accompanying this application, like numerals of reference designate corresponding parts throughout the several views, in which—

Figure 1 is a vertical sectional view of our improved clutch, partly in side elevation. Fig. 2 is an end view of the same. Fig. 3 is a front elevation of one of the gripping-shoes. Fig. 4 is a bottom plan of the same. Fig. 5 is a rear elevation of our improved clutch. Fig. 6 is a horizontal sectional view of the same. Fig. 7 is a front elevation of a pinion-carrying plate. Fig. 8 is a side elevation of the same. Fig. 9 is a front elevation of a supporting-

plate used in connection with the clutch. Fig. 10 is a detail view in elevation of a portion of our improved clutch.

In the accompanying drawings the reference-numeral 1 designates the end of a shaft upon which we mount our improved clutch. The clutch as constructed by us consists of a collar 2, which is secured or keyed upon the end of the shaft, as at 3. The collar is clearly illustrated in Figs. 1, 6, 9, and 10 of the drawings, and by referring to said figures it will be observed that the rear end of the collar is provided with an annular flange 4, while the forward end of the collar is provided with diametrically-opposed supporting-plates 5. Each plate is provided with a vertically-disposed guideway 6 and has its edges pierced, as at 7. This end of the collar is also provided with an annular recess 8, into which is adapted to fit a sleeve 9, carried centrally of a pinion-carrying plate 10. The pinion-carrying plate 10 consists of pierced arms 11, carrying outwardly-extending lugs 12. 12, 75 said lugs having horizontally-aligning apertures 14 formed therein. The arms 11 are pierced, as at 15, in order that they may be secured to the pierced edges of the supporting-plates 5 of the collar 2.

Mounted upon the collar 2 is the hub 16 of a pulley-wheel 17, said hub being retained upon the collar 2 by an annulus or ring 18, secured to the flanged end of the collar 2 by set-screws or bolts 19. The forward end of the hub portion 16 is considerably shorter than the rear end to accommodate the supporting-plates of the collar 2, the pinion-carrying plate, and other mechanism which will be presently described.

In the guideways 6 of the supporting-plates are mounted the shanks 20 of arc-shaped shoes 21, the outer faces of said shoes being covered with Babbitt metal 22 to frictionally engage the inner sides 23 of the pulley 17. 95 The shanks 20 of the shoes 21 are provided with vertically-disposed racks 24, braced by central webs 25.

Revolutionally mounted between the lugs 12 12 of the pinion-carrying plate are pinions 100 26, said pinions being adapted to mesh with the racks 24 24 of the shoes 21 21.

Revolutionally mounted in the sleeve 9 of the pinion-carrying plate is an outwardly-ex-

tending rod 27, said rod having an enlarged threaded section 28, while upon its outer end is fixed a hand-wheel 29. Revolubly mounted upon the rod 27 is a sleeve 30, the bore 31 of said sleeve being threaded, as at 32, to engage the threaded enlarged section 28 of the rod 27. The inner end of the rod 27 is contracted and provided with peripheral threads, as at 32', to receive a nut by means of which 10 the rod is retained in the sleeve 9 and the sleeve 30 is contracted, as at 31'. Upon the contracted end of the sleeve 30 is mounted a rack-sleeve 33, adapted to mesh with the pinions 26 26. The sleeve 33 is retained 15 upon the contracted end 31' of the sleeve 30 by a nut 34. The outer end of the sleeve 30 is provided with a conventional form of hand-wheel 35, said wheel being of a larger diameter than the hand-wheel 29, carried by 20 the rod 27.

In order that the mechanism just described may be dust-proof and free from danger of being struck by a moving object, we incase said mechanism within the end of 25 the pulley 17 by a cap or hood 36. The cap or hood is provided with a central opening 37 to permit of the free movement of the sleeve 30 and the rod 27, and said cap or hood is secured to the peripheral edges of the pulley 17 30 by a plurality of set-screws or bolts 38.

In practice the shaft 1 may be a revoluble element entirely independent of the pulley 17, or vice versa; but in describing the general operation of our improved clutch we 35 will assume that the shaft 1 is continually revolving and at predetermined times it is desired to revolve the pulley 17 in unison with said shaft. By the construction of our improved clutch it will be observed that the 40 collar 2, the supporting-plates 55, the pinion-carrying plate 10, the pinions 26, and the shoes 21 all revolve with the shaft 1 when it is in operation, the pulley 17 being entirely independent of any movement of the shaft 1, 45 except when our improved mechanism is operated to place the shoes 21 in engagement with said pulley.

In the accompanying drawings we have 50 illustrated the shoes 21 21 as being disengaged from the pulley 17, and in case it is desired to move said shoes into engagement with the inner sides 23 of the pulley the hand-wheel 29 of the rod 27 is gripped with one hand, while the hand-wheel 35 of the sleeve 55 30 is partially rotated with the other. The rotation of the sleeve 30 upon the threaded section 28 of the rod 27 partially revolves the pinions 26 through the medium of the rack-sleeve 33, and as said pinions partially rotate the shoes 21 21 are moved into engagement with the pulley 17 and the shoes 21 21 and the pulley 17 move in unison with the shaft 1.

Should it be desired to release the shoes,

the hand-wheel 29 is gripped, and as the rod 65 27 is held stationary the revolving of the sleeve 30 upon the threaded enlargement 28 of the rod causes the rack-sleeve 35 to move outwardly, partially rotating the pinions 26 26 and withdrawing the shoes 21 21 from the 70 pulley 17.

From the foregoing operation it will be observed that the shoes are automatically released when the hand-wheel 29 is held stationary, the rod 27, upon which the hand-wheel is mounted, being rotatable independently of the revolving collar 2 and its appurtenant parts.

It is obvious that in connection with the pulley-wheel 17 a belt will be used, and in 80 some instances the pulley may represent the revoluble member, while the shaft 1 may be temporarily stationary until the shoes are placed in engagement with the pulley-wheel.

Such changes in the construction and operation of our improved clutch as are permissible by the appended claims may be resorted to without departing from the spirit and scope of the invention.

What we claim, and desire to secure by 90 Letters Patent, is—

1. In a clutch, the combination with a revoluble shaft, of a collar fixed upon said shaft, supporting-plates carried by said collar, said plates having guideways formed therein, 95 pinion-carrying plates secured to said supporting-plates, a pulley revolubly mounted upon said collar, shoes mounted within said pulley and adapted to engage the inner sides thereof, racks carried by said shoes and engaging in the guideways of said supporting-plates, pinions journaled in said pinion-carrying plate, an outwardly-extending rod mounted in said pulley, a sleeve mounted upon said rod, means movable with said 100 sleeve to move said shoes into engagement with said pulley, substantially as described.

2. In a clutch, the combination with a shaft, a pulley journaled upon said shaft, shoes mounted in said pulley and rotatable 110 with said shaft pinion-carrying plates carried by said shaft, pinions journaled in said pinion-carrying plates and rotatable with said shaft, said pinions being adapted to engage said shoes, movable means mounted 115 within the interior of said pulley and rotatable independently of said shaft, to rotate said pinions, substantially as described.

3. The combination with a shaft, a collar fixed upon said shaft, a pulley journaled 120 upon said collar, shoes adapted to engage said pulley, of racks carried by said shoes, pinions carried by said collar and adapted to engage said racks, a rack-sleeve supported by said collar and engaging said pinions, 125 means to longitudinally move said sleeve and thereby rotate said pinions, substantially as described.

4. The combination with a revoluble shaft, a pulley-wheel, shoes carried by said shaft and adapted to engage said pulley-wheel, of racks carried by said shoes, pinions engaging said racks, a rack-sleeve engaging said pinions, means engaging said sleeve to longitudinally move the rack-sleeve and thereby move said shoes, substantially as described.

In testimony whereof we affix our signatures in the presence of two witnesses.

JOHN J. CAMPBELL.
HIRAM C. JOHNSON.
